ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

PROCESS OF MAKING SHOES.

1,117,086.

Specification of Letters Patent. Patented Nov. 10, 1914.

Application filed October 12, 1912. Serial No. 725,476.

To all whom it may concern:

Be it known that I, ADAM H. PRENZEL, a citizen of the United States, residing at Halifax, in the county of Dauphin and State of Pennsylvania, have invented certain Improvements in Processes of Making Shoes, of which the following description, in connection with the accompanying drawings, is a specification, like reference characters on the drawings indicating like parts in the several figures.

This invention relates to processes of making shoes and is herein described and illustrated in its bearing upon the manufacture of shoes of the type commonly termed "stitch-downs."

The principal difficulties heretofore experienced in the manufacture of stitch-down shoes have been in shaping the upper to the last and securing it either temporarily or permanently to the sole with a flange out-turned preparatory to the final sole attaching operation. The lasting problem is substantially the same with this type of shoe whether the shoe be of the single sole type, or whether it be provided with an insole. In attempting to solve this problem and to overcome the well-known difficulties a great many processes of making stitch-down shoes, which involve lasting the upper and securing the upper to the last or to the sole to hold it in shape for the final sole attaching operation, have been devised and a great variety of means have been utilized for securing the upper and sole in lasted position. All of these processes have proved, however, to be more or less unsatisfactory.

The dissatisfaction with the processes and means heretofore employed has arisen from a number of causes. In the practice of some processes the desire to use certain means for securing the parts in lasted position has resulted either in very imperfect shaping of the upper to the last, or in the mere connecting of the upper to the last without substantial stretching. In the practice of other processes, temporary securing means have been so located as to interfere with the proper location of the means for permanently attaching the upper to the sole, with

the result that, when the temporary securing means have been withdrawn, the shoe loses its lasted shape.

The process of making stitch-down shoes which has been in most general use up to the present time, particularly in the manufacture of the larger sizes of shoes has involved assembling the upper and the sole upon a last, and then turning the lower margin of the upper out and cementing it to the projecting margin of the sole. Even by this process it will be obvious that no proper shaping of the upper to the last can be effected, particularly in the region of the shank, and that stretching the upper to conform it to the last is practically out of the question.

The general object of the present invention is an improved process of making shoes, especially applicable to the manufacture of stitch-down shoes, whereby the upper may be properly conformed to the shape of the last and firmly secured in lasted position by attaching it to the sole, and whereby the lasting operation is so performed and the upper is so secured in lasted position as to facilitate the final sole attaching operation and to permit that the fastenings employed in the final sole attaching operation may be so located as still further to prevent the upper from losing its lasted shape.

A particular object of the invention is an improved process of making stitch-down shoes in which permanent, individual fastenings, preferably of the staple type, are utilized in the lasting process in such manner that they reinforce the attachment of the upper to the sole as well as secure the upper in lasted position for the final sole attaching operation.

In the accompanying drawings,—Figure 1 is a perspective view of a sole which may conveniently be used in carrying out the process of this invention; Fig. 2 shows a portion of a suitable means for carrying out the process; Fig. 3 shows a stitch-down shoe after it has been lasted by the process of this invention and before the sole has been finally secured to the upper; Fig. 4 shows the completed shoe; and Fig. 5 is a sectional detail

showing the location of the different parts of the shoe and the fastenings which unite these parts.

It will be understood that the process of 5 this invention may be employed in making shoes of various kinds and that the particular shoe herein shown has been selected merely for convenience in describing and illustrating the process.

- 10 In making stitch-down shoes it is usually desirable to provide some support for the upper upon the inside of the shoe so that the upper will not tend to break away from the welt and thus leave a crack in which dirt 15 may accumulate. Such support for the upper is provided in various ways, as, for example, by providing an insole which extends only to the edge of the last, or, as in the shoe herein shown, providing a shouldered sole 20 having a portion which does not extend beyond the edge of the last. Such a sole is shown in Fig. 1 and may be made in various ways, as, for example, by the process described in my co-pending application Serial 25 No. 725,479, filed Oct. 12, 1912. The raised portion 2 of this sole is cut to such an outline that its edge 4 lies flush with the bottom edge of the last when the sole is placed upon the last. The margin 6 projects beyond the 30 bottom edge of the last and is utilized in attaching the sole to the upper. Although it is preferable to provide inside support for the upper, such as herein shown, it will be obvious that so far as the process of this invention is concerned the projecting margin 6 of the sole may lie flush with the upper face of the remainder of the sole. In several of the claims the expression has been used "in the angle between the last and the 35 sole margin". Inasmuch as the practice of the process of this invention is the same whether the upper be forced into the angle between the shoulder 4 and the margin 6 or between the last 8 and a sole margin which 40 is substantially flush with the bottom face of the last, it will be understood that this expression is intended to apply to the lasting of stitch-down shoes of any type, whether such shoes have shouldered soles or 45 plain soles or whether they are also provided with insoles.

The sole and upper having been assembled upon the last 8, the angle 10 between the upper and its outturned flange is forced 55 into the angle between the last and the sole margin or into the angle 12 between the shoulder 6 and the marginal portion of the sole shown in Fig. 1, and staples are then inserted in the angle 10 through the upper 60 into the sole either in the angle between the last 8 and the sole margin or, as in the case of shouldered soles such as shown in Fig. 1, in the angle 12 between the shoulder 4 and the margin 6. These staples are so inserted

that the heads 14 of the staples lie in close 65 proximity to, and parallel to, the bottom edge of the last and also preferably so that the legs 16 of the staples are inclined to the face of the sole and extend beneath the last, but preferably not through the sole since 70 they would tend to discolor the finished bottom face of the sole. It will thus be seen that the legs of the staples are not only out of the way of the succeeding fastening by 75 which the sole is secured to the upper, but that they also extend into the sole in directions which are substantially transverse to the directions of pull of the stretched upper.

A convenient means for performing the 80 foregoing operations is the machine disclosed in my co-pending application Serial No. 725,477 filed Oct. 12, 1912 for Letters Patent for improvements in machines for lasting boots and shoes. A portion of this 85 machine is shown in Fig. 2, the parts there shown being relatively movable to effect the forcing of the upper into the angle between the last and the sole margin.

In lasting the shoe the preferable practice, 90 when the last is of the type shown in the drawings, that is, when the toe of the last is somewhat higher than the portion immediately behind it, is first to secure the heel end of the upper to the sole, then to draw 95 down the upper upon one side of the last behind the toe portion and secure it to the sole upon this side, then to draw down the upper upon the opposite side of the last and secure it to the sole upon that side, after 100 which the upper may be lasted through the shank and about the toe. The staples used are preferably of fine wire.

When the heel end of the upper and the counter are both to be provided with out-turned sole attaching flanges, as shown in the drawings, it is preferable to mold these parts of the upper before the lasting operation. Moreover when a comparatively heavy stiffener is to be provided in the toe 110 end of the upper, or when the upper stock is comparatively heavy, it is also sometimes advantageous to mold the toe end of the upper before the lasting operation.

The shoe having been lasted, as shown in 115 Fig. 3, the upper is trimmed back from the edge of the sole a short distance, as shown in Fig. 5, in order that it may not interfere with finishing the edge of the sole and a welt 18 is then laid upon the upper flange, 120 this welt being of a width sufficient to extend to the edge of the sole and being thicker upon its outer edge than upon its inner edge so that it will reach down over the edge of the upper flange into contact 125 with the upper face of the sole margin, thereby closing up any gap which might be caused by the interposition of the upper be-

tween the welt and the sole and providing a tight edge which may easily be finished in the succeeding edge finishing operations. The welt 18 is then secured to the sole by 5 stitches 20 which also pass through the upper, as shown in Fig. 5.

The novel shoe produced by the process hereinabove described is not herein claimed but is made the subject matter of my co-pending application Serial No. 863,128, filed 10 September 23, 1914, the said co-pending application being a division of this application.

Having described my invention, what I 15 claim as new and desire to secure by Letters Patent is:—

1. That improvement in the art of making shoes which consists in assembling upon a last an upper and a sole, progressively shaping 20 the upper to the last and securing the upper to the sole, as the shaping progresses, by staples driven through the upper into the face of the sole which is adjacent to the last, with the bodies of the staples parallel to 25 the last.

2. That improvement in the art of making shoes which consists in assembling upon a last an upper and a sole, progressively shaping 30 the upper to the last and securing the upper to the sole, as the shaping progresses, by staples driven through the upper into the face of the sole which is adjacent to the last, with the bodies of the staples parallel to the last and in position to hold the upper tight 35 against the side faces of the last.

3. That improvement in the art of making shoes which consists in assembling upon a last an upper and a sole, progressively shaping 40 the upper to the last and permanently securing the upper to the sole after each shaping step by an individual fastening driven through the upper into the face of the sole which is adjacent to the last, said fastening being so located and of such construction that its dimensions all lie substantially 45 in a plane parallel to the last.

4. That improvement in the art of making shoes which consists in assembling upon a last an upper and a sole having a projecting 50 margin, progressively shaping the upper to the last and securing the upper to the sole, as the shaping progresses, by staples driven through the upper into the face of the sole which is adjacent to the last, and substantially 55 in the vertex of the angle between the last and the sole, with the bodies of the staples parallel to the last.

5. That improvement in the art of making shoes which consists in assembling upon a 60 last an upper and a sole which has a margin projecting beyond the bottom edge of the last, progressively shaping the upper to the last and permanently uniting the upper to the sole, as the shaping progresses, by staples

driven through the upper into the upper face 65 of the sole in close proximity to said bottom edge of the last, with the bodies of the staples parallel to said edge.

6. That improvement in the art of making shoes which consists in assembling upon a 70 last an upper and a sole which has a margin projecting beyond the bottom edge of the last, progressively shaping the upper to the last and forcing it into the angle between the last and the projecting sole margin and 75 under the overhanging portions of the last, and driving staples through the upper into the sole in close proximity to the last, as the shaping progresses, with the planes determined by the greater dimensions of said 80 staples extending parallel to the edge of the last, whereby said staples may remain permanently in the shoe.

7. That improvement in the art of making shoes which consists in assembling upon a 85 last an upper and a sole which has a margin projecting beyond the edge of the last, progressively shaping the upper to the last and pressing it into the angle between the last and the projecting sole margin, and driving 90 a staple through the upper into the sole, after each shaping and pressing step, in such manner that the legs of the staple extend into the sole beneath the last while the head of the staple extends parallel to the edge 95 of the last and in close proximity thereto.

8. That improvement in the art of making shoes which consists in assembling upon a last an upper and a sole which projects beyond the edge of the last and progressively 100 shaping the upper to the last and permanently securing the upper and sole in lasted condition by staples of fine wire driven through the upper into the sole in the angle between the last and the projecting portion 105 of the sole, as the shaping progresses, with the bodies of said staples arranged in a line in close proximity to the edge of the last.

9. That improvement in the art of making shoes which consists in assembling upon 110 a last an upper and a sole which has a margin projecting beyond the bottom edge of the last, progressively shaping the upper to the last and forcing it into the angle between the last and the sole, and permanently 115 uniting the upper and the sole as the shaping progresses, by staples driven through the upper into the sole in a direction substantially transverse to the direction of the pull of the stretched upper, with the bodies of 120 the staples parallel to said bottom edge of the last.

10. That improvement in the art of making stitch down shoes which consists in assembling upon a last an upper and a sole 125 which has a margin projecting beyond the bottom edge of the last, turning out the lower margin of the upper, progressively

forcing the angle of the upper into the angle between the last and the sole margin and permanently securing the upper to the sole by staples inserted along the edge of the last, as the lasting progresses, with the planes determined by the greater dimensions of the staples extending parallel to said edge and in close proximity thereto, laying a welt upon the upper flange, and then uniting the welt, upper and sole with stitches.

11. That improvement in the art of making stitch down shoes which consists in assembling upon a last an upper and a sole which has a margin projecting beyond the edge of the last, turning out the lower margin of the upper, progressively forcing the angle of the upper into the angle between the last and the sole margin and permanently securing the upper to the sole by a staple driven through the upper into the sole in said angle after each forcing step, with the body of the staple in a plane parallel to the edge of the last and in close proximity thereto and so inclined to the bottom of the last that the legs of the staple extend beneath the last, laying a welt upon said upper margin, and then uniting the welt, upper and sole with stitches.

12. That improvement in the art of making shoes which consists in assembling upon a last an upper and a sole which has a margin projecting beyond the bottom edge of the last, progressively forcing the upper into the angle between the last and the projecting sole margin and uniting the upper and the sole by staples driven through the upper into the sole, as the lasting progresses, in directions transverse to the direction of pull of the stretched upper and in close proximity to said bottom edge with the bodies of the staples parallel to said edge, laying a welt upon the upper flange and then uniting the welt, upper and sole with stitches.

13. That improvement in the art of making stitch down shoes which consists in assembling upon a last an upper and a sole which is provided with a shoulder substantially flush with the edge of the last and which has a margin projecting beyond said edge, turning out the lower margin of the upper and progressively forcing the angle of the upper into the angle between the shoulder and the sole margin, permanently uniting the upper and the sole by staples inserted in said angles, as the lasting progresses, with the planes determined by the greater dimensions of said staples extending parallel to the edge of the last and in close proximity thereto, and then uniting the upper and the sole with stitches.

14. That improvement in the art of making shoes which consists in assembling upon a last an upper and a sole which has a margin

projecting beyond the bottom edge of the last, turning out the lower edge of the upper, forcing the angle of the upper into the angle between the last and the sole margin in a step-by-step manner, and securing the upper to the sole after each of the aforementioned steps by an individual permanent fastening.

15. That improvement in the art of making shoes which consists in assembling upon a last an upper and a sole having a projecting margin, turning out the lower edge of the upper, forcing the angle of the upper into the angle between the last and the sole margin in a step-by-step manner and securing the vertex of the upper angle in the vertex of the angle between the last and the sole margin after each of the aforementioned steps by an individual fastening inserted in said vertices.

16. That improvement in the art of making shoes which consists in assembling upon a last an upper and a sole which has a margin projecting beyond the bottom edge of the last, turning out the lower edge of the upper, forcing the angle of the upper into the angle between the last and the sole margin in a step-by-step manner, and securing the upper to the sole after each of the aforementioned steps by a staple having its body parallel to the edge of the last and in close proximity thereto.

17. That improvement in the art of making shoes, which consists in molding the heel end of an upper substantially to the shape of the heel end of a last, assembling upon a last said upper and a sole which has a margin projecting beyond the bottom edge of the last, turning out the lower edge of the upper, progressively shaping the forepart of the upper to the last, and permanently uniting the upper to the sole, as the shaping progresses, by staples inserted through the upper into the sole in close proximity to said bottom edge of the last with the bodies of the staples parallel to said edge.

18. That improvement in the art of making shoes which consists in molding the heel end of an upper and a counter to the shape of the heel end of a last and providing upon said parts outturned flanges, assembling upon a last said upper and counter and a sole which has a margin projecting beyond the bottom edge of the last, turning out the lower edge of the remaining portions of the upper, fitting the upper to the last by forcing the angle of the upper into the angle between the last and the sole margin in a step-by-step manner and permanently securing the upper to the sole after each of the aforementioned steps by a staple having its body parallel to the edge of the last and in close proximity thereto.

19. That improvement in the art of making shoes which consists in molding an upper and a counter to the shape of the heel end or a last and providing an outturned flange on each of said parts, assembling upon a last said upper and counter, and a sole which has a margin projecting beyond the bottom edge of the last, uniting the upper and counter at the back to the sole by a staple inserted through the upper and counter into the sole with the body of the staple parallel to the edge of the last and in close proximity thereto, turning out a flange upon the forepart of the upper, forcing the angle of the upper into the angle between the last and the sole margin upon one side of the last and securing it in lasted position by a staple inserted through the upper into the sole in substantially the same manner as the staple inserted at the heel end, performing a similar operation upon the other side of the last, and then lasting the upper in the same manner about the remaining portions of the last.
20. That improvement in the art of making shoes which consists in molding the heel and toe ends of an upper to the shape of the corresponding portions of a last and providing upon said parts outturned flanges, assembling upon a last said upper and a sole which has a margin projecting beyond the bottom edge of the last, forcing the angle of the upper into the angle between the last and the sole margin in a step-by-step manner and permanently securing the upper to the sole after each of the aforementioned steps by a staple having its body parallel to the edge of the last and in close proximity thereto.
21. That improvement in the art of making shoes which consists in assembling upon

a last an upper and a sole which has a margin projecting beyond the bottom edge of the last, turning out the lower edge of the upper, progressively shaping the upper to the last and forcing the angle of the upper into the angle between the last and the sole margin and permanently securing the upper to the outsole in said angle as the shaping progresses, trimming the edge of the upper back from the edge of the sole, placing upon the outturned upper a welt which is thicker at its outer edge than at its inner edge whereby it overhangs the trimmed back margin of the upper and uniting the welt, upper and sole.

22. That improvement in the art of making shoes which consists in assembling upon a last an upper and a sole which has a margin projecting beyond the bottom edge of the last, turning out the lower edge of the upper, forcing the angle of the upper into the angle between the last and the sole margin in a step-by-step manner, securing the upper to the sole after each of the aforementioned steps by a staple having its body parallel to the edge of the last and in close proximity thereto, trimming back the edge of the upper from the edge of the sole, laying upon the outturned part of the upper a welt which is thicker at its outer edge than at its inner edge whereby it overhangs the trimmed back portion of the upper, and uniting the welt, upper and sole with stitches.

In testimony whereof I have signed my name to this specification in the presence of two subscribing witnesses.

ADAM H. PRENZEL.
